(57) **CLAIM**

The ornamental design for a camera for liquid crystal projector, as shown and described.

DESCRIPTION

FIG. 1 is a top, front and left side perspective view of a camera for liquid crystal projector showing my new design, FIG. 2 is a front elevational view thereof, FIG. 3 is a left side elevational view thereof, FIG. 4 is a right side elevational view thereof, FIG. 5 is a rear elevational view thereof, FIG. 6 is a bottom plan view thereof, FIG. 7 is a top, front and left side perspective view in a reduced size showing the article with an arm and a stand in a moved position thereof, FIG. 8 is a top plan view thereof, and; FIG. 9 is a reference view showing the article in use thereof. The broken line showing of a projector portion in FIG. 9 is for illustrative purposes only and forms no part of the claimed design.
